PHASE MODULATION SYSTEM

Jozef Plebanski, Warsaw, Poland, assignor to Radio Patents Corporation, a corporation of New York

Application June 20, 1940, Serial No. 341,486
In Poland August 21, 1937

2 Claims. (Cl. 179—171.5)

This application is a continuation in part of my application Serial No. 224,061, filed August 10, 1938, entitled "Electric control system."

The present invention relates to radio systems and more particularly to an improved system for and a method of phase modulating a high frequency carrier wave in accordance with a signal frequency wave.

An object of the invention is to provide a novel phase modulating system and a method of operating same which is both simple in design and characterized by increased efficiency compared with phase modulating systems known in the prior art.

Another object is to effect a phase modulation of a high frequency carrier wave by the employment of purely electrical means, that is, without requiring devices having mechanically moving parts.

The above and further objects and advantages of the invention will become more apparent from the following detailed description taken with reference to the accompanying drawings forming part of this specification and wherein:

Figure 1 is a circuit diagram for a radio transmitter embodying a phase modulating system according to the invention.

Figures 2 and 3 are graphs explanatory of the function and operation of the system according to Figure 1.

Figure 4 is a circuit diagram of a simplified phase modulation system embodying the principles of the invention, and

Figure 5 is a graph explanatory of the function of Figure 4.

Like reference characters identify like parts in the different views of the drawings.

Referring to Figure 1, items 10, 11 and 12 represent electron discharge tubes shown as triodes amplifiers but which, as will be understood, may be of any suitable type well known in the art. The control grids of all three tubes are simultaneously excited by a carrier frequency potential supplied by a suitable source such as a master oscillator 13 and impressed upon the grids in any suitable manner such as by way of tuned high frequency transformers 14, 15 and 16, respectively, as shown in the example illustrated. The control grids of the tubes 10, 11 and 12 are additionally excited by a modulating potential supplied from a suitable source such as from the output of a microphone circuit or the like and impressed upon the grids by way of low frequency transformers 18, 19 and 20, respectively. In the example shown the grids of tubes 10, 11, 12 are 55

energized by the carrier and modulating potentials by connecting the primaries of transformers 14, 15, 16 and 18, 19, 20 in series with the master oscillator 13 and the source of modulating potential (terminal posts 17), respectively. Any other excitation such as parallel connection or mixed connection of the grids to the carrier and modulating signal sources may be employed as will be readily understood. The grids of the tubes 10, 11 and 12 are suitably biased (steady grid bias) in a manner to be described presently such as by the aid of biasing batteries 21 and 21' or network 22 comprising a resistance shunted by a condenser inserted in the cathode-to-ground leads in a manner well known. The output of tube 10 is applied by way of coupling coil 25 to a resonant circuit comprising an inductance coil 26 shunted by a condenser 27 having in series therewith a coupling coil 31. The tubes 11 and 12 are excited by the modulating potential in anti-phase relation or push-pull by proper connection of the primary windings of the modulating transformers 19 and 20, respectively. The outputs of the tubes 11 and 12 are combined in push-pull relation by applying in a known manner the positive anode potential for the tubes to the center tap of the primary winding 28 of a common output transformer having a secondary 29 forming a further resonant circuit together with a condenser 30 having in series therewith a coupling coil 32.

The resonant circuits 26—27—31 and 29—30—32 are tuned to the carrier frequency and are reactively coupled with each other, in the example shown through the coupling coils 31 and 32 being in inductive coupling relation with each other. By suitable design of the circuit constants this resonant circuit arrangement constitutes a phase shifting system of the type disclosed in greater detail in my U. S. Patent No. 2,172,107 issued September 5, 1939. If, as described in said patent, in a twin resonant circuit of this type comprising a pair of reactively coupled resonant circuits both circuits are excited separately by signals of like (resonant) frequency, then the time phase position of the current or potential developed in either circuit will be dependent upon the amplitude relation of the signals or potentials impressed upon the circuits. Thus, if the circuits are designed in such a manner that the non-reactive (ohmic or loss) impedances of both circuits are alike and equal to the mutual coupling impedance between the circuits, the currents developed in the circuits by potentials of like amplitude separately impressed upon the circuits will have a relative phase difference of 90°.

from each other. If the relative amplitude of the signal potentials impressed upon one circuit varies in either direction, the phase difference between the currents developed in the circuits will become greater or less, respectively, than the normal 90° phase relation, the relative phase variation being proportional to the relative amplitude variation between the impressed potentials. This circuit thus constitutes a simple and efficient means for converting alternating currents of varying relative amplitude into a current of substantially equal amplitude having a phase varying in accordance with the original amplitude variation.

According to the present invention, the normal or steady grid bias for the tubes 10, 11 and 12 is adjusted in such a manner as to obtain a differential variation of the carrier current amplitudes in the circuits 26-27-31 and 29-30-32 substantially according to a sine and cosine function, respectively, in such a manner as to convert the amplitude modulations of a modulating signal applied to terminals 17 into corresponding phase variations of the currents in the resonant circuits 26-27-31 and 29-30-32. The phase modulated signal energy developed in one of the resonant circuits is then applied by way of coupling condenser 33 to a power amplifier 34 which latter feeds a utilization circuit such as an antenna 36 through a coupling transformer 35. If desired, a frequency multiplication arrangement may be embodied in the amplifier 34 to change the initial phase modulation into a corresponding frequency modulation. Moreover, current limiting devices or circuits may be provided to substantially suppress any spurious amplitude variations of the carrier signals to be transmitted.

The operation of the circuit described will be further explained in the following with reference to Figures 2 and 3.

Figure 2 is a graph showing the variation of the amplitude of the alternating (carrier) current I in the output of an amplifying tube, plotted as a function of the grid potential e . As is seen, the current I increases gradually starting at a predetermined negative grid potential ($-E_2$) as the grid potential becomes less negative and finally assumes positive values. At a definite positive grid potential ($+E_1$) the current I reaches a maximum and thereafter begins to fall as the grid is made more positive to again become zero at a definite positive grid bias ($+E_3$) when all the electrons emitted by the cathode are attracted by the grid and no current is passed to the plate or anode. Curve A in Figure 2 equals with sufficient approximation a sine or cosine half wave and this fact is made use of by the invention to obtain a differential amplitude variation of the carrier currents developed in the resonant circuit 26-27-31 and 29-30-32 in accordance with the modulating signal variations, to effect a corresponding phase modulation as will be understood from the above. By applying a bias to tube 10 in Figure 1 equal to $+E_1$ and similarly biasing the tubes 11 and 12 by potentials $-E_2$ and $+E_3$, respectively, as shown in Figure 2, operating curves A, B and C are obtained as shown in Figure 3 of which A represents the variations of the alternating or oscillating current developed in the resonant circuit 26-27-31 and B+C represents the variation of the oscillating current amplitude point O. Curve C is the mirror image of curve C' with respect to the abscissa in view of the push-pull connection of the tubes 11 and 12 energizing the

resonant circuit 29-30-32. Thus, with a modulating potential simultaneously impressed upon the grids of all three tubes, it is seen that the relative amplitudes of the carrier currents in the resonant circuits and as a result thereof the phase of either of these currents varies in proportion to the variations of the modulating signal m superimposed upon the steady grid bias of the tubes.

According to Figure 3 the normal or zero operating bias is such that the curves A and B+C are in phase quadrature whereby the circuit 29-30-32 is normally, i. e. with the modulating potential being equal to zero, excited from the circuit 26-27-31 only and the phase of the oscillating current set up in the circuit 29-30-32 will vary in either direction in proportion to positive and negative values of the modulating potential and between limits determined by the maximum amplitudes of the latter.

In the example shown, the amplitudes of the modulating potential m vary between limits $+e_0$ and $-e_1$ corresponding to like values of the current I in both resonant circuits, in which case the phase swing or deviation will be 90° in both directions. Any other phase range or depth of phase modulation may be employed to suit existing requirements. Actually a system as described and adjusted according to Figure 3 will enable a full maximum phase deviation of 180° in both directions.

If only a small phase modulation range or deviation, say 40° or less is desired, such as employed in the initial stage of present day frequency modulation transmitters, the system may be greatly simplified as shown in Figure 4 which differs from Figure 1 in that tube 12 and its associated input and output circuits are omitted and the resonant circuit 29-30-32 is energized solely by the output of tube 11. By biasing tube 10 positively by a potential $+E_4$ and by biasing tube 11 by potential $+E_5$ according to Figure 2, operating characteristics D and E with respect to a common zero point O are obtained as shown in Figure 5. As seen from the latter, when the modulating potential m is zero the currents I impressed upon both resonant circuits are equal resulting in a 90° phase relation between the currents. As the modulating potential increases in a positive or negative direction, the relative amplitude of the currents in the resonant circuits varies accordingly resulting in a corresponding increase or decrease, respectively, of the normal (90°) phase relation. In this manner a phase modulation with a maximum depth or deviation of 90° in either direction from the normal phase position may be effected in a simple and most efficient manner.

As will be evident from the above the invention is not limited to the specific details and circuit arrangements shown and disclosed herein for illustration but that modifications and variations may be resorted to differing from the specific embodiment shown in accordance with the broader scope and spirit of the invention. The specification and drawing are accordingly to be regarded in an illustrative rather than a limiting sense.

I claim:

1. A phase modulating system comprising three electron discharge devices, each comprising a cathode, an anode and at least one grid electrode, a source of carrier current to be modulated, means for simultaneously impressing potential from said source upon the grids of said devices, a

first resonant circuit tuned to the frequency of said source and fed from the output of the first of said devices, a second resonant circuit also tuned to the frequency of said source and connected to the outputs of the remaining discharge devices in push-pull, means for simultaneously impressing modulating potential upon the grids of said devices, the modulating potentials impressed upon the grids of said push-pull connected devices being of opposite polarity, further means for applying steady bias potential to the grids of said devices, the steady bias of each of said push-pull connected devices being below and above, respectively, the steady bias of said first device, and mutual reactive coupling means between said first and second resonant circuit, and a utilization circuit energized from at least one of said resonant circuits.

2. A phase modulating system comprising three electron discharge devices, each comprising a cathode, an anode and at least one grid electrode, a source of carrier current to be modulated, means for simultaneously impressing potential from said source upon the grids of said devices, a

first resonant circuit tuned to the frequency of said source and fed from the output of the first of said discharge devices, a second resonant circuit also tuned to the frequency of said source and connected to the outputs of the remaining discharge devices in push-pull, further means for simultaneously impressing modulating potential upon the grids of said devices, the modulating potentials impressed upon said push-pull connected devices being of opposite polarity, means for applying steady bias to the grids of said devices, the steady bias of each of said push-pull connected devices being above and below, respectively, the steady bias of said first device, and mutual inductive coupling means between said resonant circuits, said coupling means and the constants of said resonant circuits being designed so as to cause the alternating currents in said resonant circuits to be of substantially constant amplitude and time phase varying in accordance with said modulating potential, and a utilization circuit energized from at least one of said resonant circuits.
